Robert Allan, of Cananda, N.Y.

Assignor to

A. Smith of West Farm, N.Y.

Whole No 1366.

Gillers Patent No 1. Dated Feb. 5 1861.

The schedule referred to in these Gillers Patent and making part of the same.

That which it may concern:

I, Robert Allan, of Cananda, in the County of Oneida, in the State of New York, have invented or introduced a new and original design for carpets, and I do hereby declare that the following is a description of the same reference being had to the accompanying drawing which represents my design and forms a part of this Specification.

My design is composed of Grape leaves and Grapes, with veins and shades therein, Grapes with shade lines; Grape vines in outline, another series of Grape leaves with veins, still another outline, showing slender branches; and grounds of two different colors, all disposed and arranged

AUG. 13 1866

as shown in the drawing.

I will describe my design, more in detail, referring to the drawing and to the letters of reference thereon.

The most prominent or first objects or elements in my design are the grape leaves A, B, and their stem or branch C, represented in the drawing in yellow. The leaf A is partially superposed upon B, with a portion of the stem protruding from behind on each side of A, B. One end C of this stem is branched and exhibits an end as if broken from a larger branch. Behind and partially concealed in A, B, C, are introduced the grape vines D, E, and the grapes F, and behind these are the dark grape leaves G. The grape vines D, E, are as follows: Two nearly parallel vines D, D, extend diagonally across the Carpet in easy curves. The spaces between these vines are partially shaded with broken lines as shown by H. Corresponding vines E, E, extend diagonally in the other direction crossing D, D, at the point directly behind, or concealed by, the leaves A, B. The spaces between E, E, are also shaded by H, as shown. A number of grapes F, are distributed loosely around A, B, and are partially concealed by the vines D, E. Behind all these diagonally disposed, I, correspond therewith, and from a back line for are other grape leaves I, I, shown in the drawing in black.

The design, so far as now described, encloses irregular squares, M, N, between the diagonal series of leaves I, I. These squares are alternately in different colors, one, M, being crimson, the next N, green, the third crimson again, and so on. Shadowy grape leaves P, shown in broken parallel lines, and slender branches or twigs R, shown in black, extend out from behind the leaves I, I, into the grounds M, N, as represented.

The whole is of a sketchy and easy character and is enriched by shade lines in full colors as represented.

I do not confine myself to the particular tints herein described. The color of any one or all of the elements of my design may be modified or changed entirely without affecting its character.

Having now fully described my combination and arrangement of ornamental figures. What I claim as new and desire to secure by Letters Patent is

The combination and arrangement of the diverses herein
